DRUM EXERCISER

Robert M. Birkenbeul and Patrick W. Johnson, Fort Wayne, Ind.; said Birkenbeul assignor to said Johnson
Filed Feb. 23, 1962, Ser. No. 175,366
6 Claims. (Cl. 272—57)

The present invention relates to a drum exerciser, and more particularly to a mechanism having a rotatable drum thereon which may be manipulated at the will of the operator.

It is well known that physical exercise tends to reduce weight. It is also recognized that certain types of massage aids in the reduction of weight and the dissolution of fat in particular localized areas of the body, and to this end many different contrivances have been used for the purpose of providing massage as well as a limited amount of exercise.

The present invention relates to a mechanism whereby both massage and exercise may be simultaneously obtained, this mechanism being particularly useful in the exercising of the arms and other parts of the body as well as the reduction of weight in the hip and leg portions.

It is an object of this invention to provide an exerciser which is manually operable and may be used to not only massage the hips, legs, stomach, back and the like but at the same time provides exercise for the arms, back, stomach and other portions of the body.

It is a further object of this invention to provide a drum which may be operated by an individual in such a manner that the person may roll on it with different parts of his body in contact therewith, the mechanism providing handles which may be adjusted to different positions for the purpose of facilitating different types of exercises.

Other objects will become apparent as the description proceeds.

The above-mentioned and other features and objects of this invention and the manner of attaining them will become more apparent and the invention itself will be best understood by reference to the following description of an embodiment of the invention taken in conjunction with the accompanying drawings wherein:

FIG. 1 is an end view of an embodiment of this invention; and

FIG. 2 is a longitudinal sectional view taken substantially along section line 2—2 of FIG. 1.

Referring to the drawings, a supporting frame or stand comprises four legs which are assembled in end pairs 10 and 12, respectively. Each end pair of legs 10 and 12 is assembled together in the form of an A-frame wherein the upper ends thereof are secured together by means of a supporting or socket plate 14 preferably formed by stamping from self-supporting sheet metal. The plate 14 is substantially U-shaped in cross-section as is more clearly shown in FIG. 2 with the opposite sides 16 and 18 thereof having halves of socket portions formed therein to provide two angularly related sockets 20 and 22. These sockets 20 and 22 receive the upper ends respectively of the legs 10 and 12. Preferably, the inside diameters of these sockets 20 and 22 are substantially coextensive with the outer diameters of the legs 10 and 12 such that the legs have a frictional fit with the sockets.

Once the legs are assembled into the sockets, a bolt or screw 24 is passed through the sides 16 and 18 of the socket plate 14 for the purpose of drawing them together whereby the sockets 20 and 22 clamp securely onto the upper ends of the legs 10 and 12.

The plates 14 are provided each with a straight upper edge 26 having a part cylindrical recess 28 formed therein between the ends. As shown in both figures, an elongated

2

bar 30 which may be circular in cross-section has its opposite ends cradled in the recesses 28 whereby the bar 30 is supported in horizontal position as shown. A radial portion of the bar 30 extends upwardly out of the recesses 28 for a purpose which will become apparent from the following description.

A clamping bar indicated by the numeral 32 is secured to the upper edge of the plate 14 by means of bolt and nut assemblies 34 and 36, the bolt and nut assembly 34 being attached to the supporting plate 14 on one side of the recess 28 as shown in FIG. 1 while the assembly 36 is fastened to the plate 14 on the opposite side of the recess 28. The clamping bar 32 is preferably made of solid steel such that when the bolt and nut assemblies 34 and 36 are tightened, the bar 32 will be clamped tightly against the bar 30, forcing the latter into the respective socket 28. The supporting bar 30 is thereby held against rotation with respect to each supporting plate 14.

Preferably, the bolt and nut assembly 36 uses a thumb nut 38 which can be manually tightened and loosened. By this means, the clamping bar 32 may be clamped and unclamped selectively from the supporting bar 30. However, in normal operation the nut 38 is turned down tightly enough so as to securely clamp the bar 32 against the supporting bar 30.

Rotatably mounted on the supporting bar 30 is a drum assembly indicated generally by the reference numeral 40. This drum assembly comprises a tubular shaft 42 which is telescoped over the supporting bar 30 and which is rotatable thereon. Welded to the shaft 42 are a plurality of radially outwardly extending discs 44 which are preferably fabricated of relatively thick sheet steel for a purpose which will become apparent from the following description.

Each disc 44 is provided with a radial recess 46 in the outer periphery thereof as shown more clearly in FIG. 1. On the outer peripheries of these discs 44 is welded or otherwise secured a cylindrical shell of relatively stiff sheet metal 48, this shell 48 having an axial slot formed by the opposite ends thereof which are curved as shown at 50. These curved ends 50 fit into the recesses 46 of the discs 44 so that the cylindrical contour of the drum shell 48 will not be interrupted. However, the ends 50 are spaced apart to provide a slot as previously mentioned for a purpose which will be described in the following.

On the outer periphery of the shell 48 is mounted a sheet of foam rubber or the like material 52, the opposite ends 54 of this sheet extending into the recesses 46 of the plates 44 and into the slot formed between the ends 50 of the shell 48. In order to secure the foam rubber sheet 52 in place, an elongated wedge 56 of hard rubber or the like material is fitted into the slot formed between the shell ends 50 as shown in FIG. 1 thereby clamping the respective foam rubber ends 54 against the curved ends 50 of the shell 38. By this means, the sheet 52 of foam rubber is securely locked onto the outer periphery of the drum shell 48.

A pair of handles 58 are removably secured to the opposite ends of the supporting bar 30, respectively, adjacent to the drum assembly 40. Each of these bars 58 is clamped in position by means of a clamping block 60 which is provided with an opening 62. The block 60 is also formed with a longitudinally extending slot 64 which extends through the opening 62. The supporting bar 30 passes through the block opening 62 and the block 60 is securely clamped onto the bar 30 by means of a bolt 66 passed through the lower ends of the block 60 to squeeze the furcations together, these furcations being formed by the slot 64.

When the mechanism is completely assembled as described, the supporting bar 30 is held stationary in the

supporting plates 14. The drum assembly 40 is rotatable about the supporting bar 30 and the handles 58 are stationary and extend in the embodiment shown in an upright position. However, if it is desired to swing the handles 58 to some other position, it is only necessary to loosen the nuts whereby the supporting rod 30 may be rotated in a position which will swing the handles 58 to the proper position. Following this, the nuts 36 are tightened to clamp the supporting rod 30 against rotation.

In the preferred embodiment of this invention, the drum assembly 40 is approximately one foot in diameter and approximately two feet in length whereby a user will ordinarily have ample space within which to sit or lie on the drum while operating the same. While the mechanism may be used in any manner which may be desired, one contemplated method of use is for the person to sit on the drum assembly 40 grasping the upper end of the handles 58 in his hands. By means of force exerted by the arms, the person may roll himself to and fro over the drum, thereby massaging the buttocks region. In another method of using the exerciser, the handles 58 may first be rotated to a position at which they are angled downwardly following which a person may lie with his stomach on the drum while gripping the handles 58 in his hands. By exerting suitable force on the handles 58, the person may thereupon roll himself on the drum to and fro, thereby massaging and exercising his midsection.

As will now become apparent, the exerciser may be used in any number of different manners, the handles 58 always being positioned suitably to permit the particular exercise desired.

While we have described above the principles of our invention in connection with specific apparatus, it is to be clearly understood that this description is made only by way of example and not as a limitation to the scope of our invention.

What is claimed is:

1. An exercising device comprising a supporting stand; said stand including two spaced-apart leg sets; each leg set including a pair of elongated leg members joined together in the form of an A-frame by means of a socket plate; said socket plate being a rigid structure of sheet steel of generally U-shape and having a pair of opposite parallel sides and elongated sockets therein, said sockets having axes which intersect in an angle, said axes defining a plane which is parallel to the sides of said socket plate, said socket plate also having an upper edge in which is provided an arcuate recess, the intersection of said axes coinciding with the center of said recess, said pair of sockets receiving the respective ends of said pair of leg members; an elongated bar having the opposite end portions cradled in the recesses of the two socket plates; a drum rotatably mounted on said bar, said drum comprising a tubular shaft telescoped over said bar and rotatably mounted thereon, a plurality of rigid sheet metal discs fixedly secured to said shaft and axially spaced apart thereon, said discs being parallel to each other and lying in planes normal to said shaft, said discs each having a recess in the periphery, all of the disc recesses being axially aligned, a tubular shell of sheet metal surrounding and secured to the outer peripheries of said discs, said shell having an axially extending slot therein in registry with said disc recesses, a sheet of foam rubber-like material mounted on said tubular shell and having opposite ends which enter said slot and said disc recesses, an elongated wedge fitted into said slot and frictionally engaging the opposite ends of said sheet of rubber-like material for securing the latter in place; each said socket plate having a clamping bar thereon which engages said elongated bar and clamps the latter in the socket plate recess, said clamping bar removably securing said elongated bar against rotation, bolt assemblies removably securing the clamping bar to the socket plate; and a pair of handles secured to said elongated bar adjacent the opposite ends respectively of said drum, said handles extending radially out-

wardly from said elongated bar whereby they may be gripped by a person mounted on said drum.

2. The exercising device of claim 1 wherein said socket plate further comprises a straight upper edge in which the recess is disposed, and said clamping bar overlies and is parallel to said edge such that said bolt assemblies connect said clamping bar to said socket plate on opposite sides respectively of the socket plate recess.

3. An exercising drum comprising a supporting stand; said stand including supporting legs having secured thereto a pair of spaced apart mounting members, each mounting member having a recess therein, an elongated bar having its opposite ends mounted in the recesses, respectively, of said mounting members, at least one clamping bar removably attached to one clamping member in a position which overlies the elongated bar, said clamping bar securing said elongated bar against rotation in said recesses, a drum rotatably mounted on said bar, said drum comprising a tubular shaft telescoped over said bar and rotatably mounted thereon, a plurality of rigid sheet metal discs fixedly secured to said shaft and axially spaced apart thereon, said discs being parallel to each other and lying in planes normal to said shaft, said discs each having a recess in the periphery, all of the disc recesses being axially aligned, a tubular shell of sheet metal surrounding and secured to the outer peripheries of said discs, said shell having an axially extending slot therein in registry with said disc recesses, a sheet of foam rubber-like material mounted on said tubular shell and having opposite ends which enter said slot and said disc recesses, an elongated wedge fitted in to said slot and frictionally engaging the opposite ends of said sheet of rubber-like material for securing the latter in place; and a pair of handles secured to said elongated bar adjacent the opposite ends respectively of said drum, said handles extending radially outwardly from said elongated bar whereby they may be gripped by a person mounted on said drum.

4. An exercising drum comprising a supporting stand; said stand including supporting legs having secured thereto a pair of spaced-apart mounting members, each mounting member having a recess therein, an elongated bar having its opposite ends mounted in the recesses, respectively, of said mounting members, at least one clamping bar removably attached to one clamping member in a position which overlies the elongated bar, said clamping bar securing said elongated bar against rotation in said recesses, a drum rotatably mounted on said bar, said drum comprising a tubular shaft telescoped over said bar and rotatably mounted thereon, a plurality of rigid sheet metal discs fixedly secured to said shaft and axially spaced apart thereon, said discs being parallel to each other and lying in planes normal to said shaft, said discs each having a recess in the periphery, all of the disc recesses being axially aligned, a tubular shell of sheet metal surrounding and secured to the outer peripheries of said discs, said shell having an axially extending slot therein in registry with said disc recesses, a sheet of foam rubber-like material mounted on said tubular shell and having opposite ends which enter said slot and said disc recesses, an elongated wedge fitted into said slot and frictionally engaging the opposite ends of said sheet of rubber-like material for securing the latter in place.

5. An exercising drum comprising a supporting stand; said stand including supporting legs having secured thereto a pair of spaced apart mounting members, each mounting member having a recess therein, an elongated bar having its opposite ends mounted in the recesses, respectively, of said mounting members, at least one clamping bar removably attached to one clamping member in a position which overlies the elongated bar, said clamping bar securing said elongated bar against rotation in said recesses, a cylindrical drum rotatably mounted on said elongated bar, and a pair of handles secured to said elongated bar adjacent the opposite ends respectively of said drum, said

handles extending radially outwardly from said elongated bar whereby they may be gripped by a person mounted on said drum.

6. An exercising drum comprising a supporting stand, said stand including supporting legs having secured thereto a pair of spaced-apart mounting members, an elongated bar having its opposite ends mounted on said mounting members, respectively, means removably clamping said elongated bar against rotation to said mounting members, a cylindrical drum rotatably mounted on said elongated bar, and a pair of handles secured to said elongated bar adjacent the opposite ends respectively

of said drum, said handles extending radially outwardly from said elongated bar whereby they may be gripped by a person mounted on said drum.
